UNITED STATES PATENT OFFICE.

LUCIEN D. COLE, OF NEWBURYPORT, MASSACHUSETTS, ASSIGNOR TO THE TOWLE MANUFACTURING COMPANY, OF SAME PLACE.

DESIGN FOR A HANDLE FOR SPOONS.

SPECIFICATION forming part of Design No. 24,495, dated July 23, 1895.

Application filed March 20, 1895. Serial No. 542,544. Term of patent 7 years.

To all whom it may concern:

Be it known that I, LUCIEN D. COLE, of Newburyport, in the county of Essex and State of Massachusetts, have invented a new and original Design for the Handles of Spoons, Forks, and other Similar Articles, of which the following is a full, clear, and exact description.

Reference is to be had to the accompanying drawings, forming a part of this specification, in which similar letters of reference indicate corresponding parts in all the figures.

Figure 1 is a view of the obverse side. Fig. 2 is a view of the reverse side of a handle embodying my new design, and Fig. 3 is an enlarged cross-section on about line 3 3 of Fig. 1.

The leading feature of my design consists in the ornamentation of the front and back of the spoon, including the vase-like figure upon the obverse of the handle near its outer end, having longitudinally-ranging surfaces merging at their lower ends into foliate scrolls.

Referring to the obverse, the vase-figure *a* in its body part appears in relief and presents three surfaces at an angle to each other and ranging lengthwise, and at its base said vase merges into conventional foliate scrolls *b*, and the border-scrolls *c* that frame the vase-figure *a* rise from the scrolls *b* and curve over the body of the vase-figure toward the helical cap *a'* thereof.

The shank or narrower part of the handle presents an eight-sided figure, as seen best

in Fig. 3, beveled surfaces *g* appearing between the obverse *h* and the sides *i* and between the reverse *j* and sides *i*, said beveled surfaces being beaded, as at *e*, and at the inner end of the handle and below the scrolls *b* scrolls *f* appear; further, the beading is continued along the handle at each side, at 40 the upper end, following the lines of the scrolls *c*, that frame the vase-figure, as at *e'*.

The reverse, as will be seen from Fig. 2, presents substantially the same appearance as the obverse, having the vase-figure, scrolls, 45 and beads of the obverse but slightly modified, the vase being concaved, as at *a'*, the beads *e'* being within the scrolls *c* instead of exterior thereto, as on the obverse, and the detail at the base of the vase being modified, 50 presenting a less prominent scroll with rosette.

I claim—

1. The design for a handle for spoons or similar articles, herein shown and described. 55
2. In a design for a handle for spoons or similar articles, the obverse as herein shown and described.
3. In a design for a handle for spoons and similar articles, the reverse as herein shown 60 and described.

LUCIEN D. COLE.
